BRASSIÈRE

Dominic A. Cerrato, Newark, N. J.

Application May 2, 1947, Serial No. 745,364

3 Claims. (Cl. 2—42)

1

This invention relates to apparel and more particularly to brassières.

An important object of the invention is to provide a brassière, including portions extending over the wearer's back but which portions, owing to the novel construction and arrangement of parts of the brassière, will not tend to ride upwardly.

Another important object is to provide such a brassière which may be worn with garments cut low in the back, and the back portion of the brassière will not extend nor tend to extend above the horizontal plane nor outwardly of the vertical planes and inclined planes of the upper edges of the back portion of the garment.

Still another important object is to provide a brassière, so constructed and with the parts thereof so arranged, that there will be no puckering, wrinkling nor unsightly folding of the brassière walls.

In addition, a major object is to provide a brassière, as described, which will obviate the unsightly outwardly convex swell of the flesh above the upper edges of the brassière, where the wearer's breasts merge into the adjacent portions of the thorax.

Other objects and advantages of the invention will be apparent during the course of the following detailed description of the invention taken in connection with the accompanying drawings, forming a part of this specification, and in which drawings—

Fig. 1 is a front elevation of the new brassière, including stretchable portions with the latter under no tension.

Fig. 2 is a similar view, but with the stretchable portions under tension.

Fig. 3 is a front elevation of an end fragment of the novel brassière, with parts removed, to better illustrate portions of the construction.

Fig. 4 is a rear elevation of the end fragment of Fig. 3 and with parts not under tension.

Fig. 5 is like view, but with parts under tension.

Fig. 6 is a view, somewhat similar to Fig. 3 but with portions of the inner and outer walls of the garment partly separated in order to better illustrate the arrangement of parts.

In the drawings, wherein for the purpose of illustration is shown a preferred embodiment of the invention and wherein similar reference characters designate corresponding parts throughout the several views, the novel brassière is shown to include an intermediate breast-supporting portion 10 of any desired contour and

having an upper edge 11, and edge sections 12 and 13 and a bottom edge 14.

The brassière also includes novel end sections 15 and 16, each provided with a first wall portion 17 which, in the example shown, is the front portion, a second wall portion 18 which, in the example shown, is the rear portion, a length or first portion 19 of stretchable material, and a length or second portion 20 of stretchable material.

In addition, the brassière may include suitable shoulder straps 21 and means 22 to detachably secure together the two free extremities of the end sections 15 and 16.

15 The end sections 15 and 16 are, preferably, substantially alike, with the first wall portion 17 having an edge section 25 secured to the edge section 12, as by stitchings 26, an edge section 27 secured to the edge section 13 of the intermediate 20 portion 10, as by stitchings 28, an upper edge section 29 defining an upper edge 30, a lower edge section 31 defining a lower edge 32 and an outer edge section 33 defining an outer or end edge 34. The edge 34 forms, with the lower edge 32, an obtuse angle and forms, with the edge 30, an acute angle.

Paralleling and partly overlapping the first wall portion 17, is the second wall portion 18, having an upper edge section 35 defining an upper edge 36, a lower edge section 37, defining a lower edge 38, an outer end edge section 39 defining an end edge 40 and an edge section 41 opposite the edge section 39 defining an edge 42 opposite the edge 40. Preferably, the edges 36 and 42 form substantially a right angle, the edges 38 and 42, form an acute angle, the edges 38 and 40 substantially a right angle, and the edges 36 and 40, form an obtuse angle.

Where they overlap, the two wall portions 17 and 18, are secured together along at least a part of their lower edge sections 31 and 37 respectively as by stitchings 43 but the upper edge sections 29 and 35 are not secured together.

45 The edge 42 of the wall portion 18 is spaced from the end edges 12 and 13 of the intermediate portion 10. An average spacing of one-and-one-quarter inches is given by way of example although, of course, this spacing may vary. The end edge 40 of the wall portion 18 is spaced from the outer or end edge 34 of the wall portion 17, so that the outer edge section 39, as well as parts of the upper and lower edge sections 35 and 37 of the wall portion 18, extend outwardly (or endwardly) of the end edge 34.

Each wall portion 17 and 18 is of suitable flexible material, as cloth.

The length or first section 19 of stretchable material may be secured at one of its ends 45 to the intermediate portion 10 at adjacent the juncture of the portion 10 and wall portion 17, and is secured, at its other end 46 to the wall portion 18 at the section 41 thereof where this section joins the section 35, but it is not secured, at this end 46, to the wall portion 17. Thus, as may be seen, particularly in Fig. 6, the wall portion 18 is indirectly secured to the intermediate portion 10 by the length or first section 19, bridging the portions 10 and 18, and the portion 18 is not attached to the portion 17 along their edge sections 29 and 35. This permits wide relative play of the wall portion 18 with respect to the portion 17.

The lengths or second sections 20 of stretchable material are secured to the wall portions 17 at the latter's end sections 33. Preferably, each length 20 is looped, as in Fig. 6, and its ends 50 and 51 secured to its associated wall portion 17, one end 50 at adjacent the juncture of the sections 29 and 33, and the other end 51 at adjacent the juncture of the sections 31 and 33. Where the section 20 reaches the edge section 39 of the portion 18 it is secured thereto, as by stitchings 53.

Preferably, the lengths 19 and 20 of stretchable material are elastic, as rubber. It is not necessary that these lengths be wide. For example, they may be only one-half inch wide and will function properly.

The two straps 21 are secured, as by stitchings 55, at an end of each, to the wall portions 18, and not to the wall portions 17, at the upper edge sections 35 of the former, and may be conventionally secured, as by stitchings, to the intermediate portion 10 of the brassière.

The means 22 to detachably secure together the two free extremities of the end sections 15 and 16 may be a conventional hook 60, secured to the loop at the free end of one of sections 20 and having a slot 61 adapted to receive the loop at the free end of the other section 20.

In Fig. 1 the outermost parts of the end sections 15 and 16 are illustrated as in substantially the same plane and not under tension, and the outermost parts of the sections 15 of Figs. 3 and 4 are shown as substantially flat, and not under tension. As may be seen in Fig. 1 the lower edges of the intermediate portion 10 and end sections 15 and 16 do not converge toward the vertical medial line of the intermediate portion 10 nearly as abruptly as they do in Fig. 2, where the end sections 15 and 16 are under tension.

Since the wall portions 17 and 18 or of flexible but not, appreciably, stretchable material, the two portions 17 and 18 may take various positions with respect to each other, limited only by the stitchings 43 along their overlapping lower edge sections. Obviously, the movement of the two associated wall portions will be such that their edges 34 and 42 move toward and away from each other as there is tension applied and then removed.

When worn, the novel brassière hugs the thorax of the wearer, accommodates the flesh where the wearer's breasts merge into the adjacent portions of the thorax and, consequently, the flesh does not, as is the case with some persons, swell out above the upper edges of the end sections 15 and 16. However, the function of the novel-shaped wall portions 17 and 18 and their associated

length 19 and 20 of stretchable (elastic) material, with the portions 17 and 18 secured together along only one edge of each and the lengths 19 and 20 arranged as described, is not confined solely to this. The construction and arrangement disclosed tends to cause the portions 17 and 18, where they extend over the wearer's back, to remain in a fixed position, no matter if the wearer bends the body forwardly or backwardly or from side to side. In fact, with the arrangement described, the portions 17 and 18, where they cross the wearer's back tend to move downwardly, rather than upwardly and, in all cases, they do not tend to move upwardly of a fixed position. Consequently, when worn, the portions 17 and 18, where they cross the wearer's back do not ride up above the upper back edge of the wearer's gown.

Various changes may be made to the form of the invention herein shown and described without departing from the spirit of the invention or scope of the claims.

What is claimed is:

1. In a brassière, an intermediate breast-supporting portion having opposite end edge sections and an upper edge section; a pair of end sections, one extending outwardly from one end edge section and the other extending outwardly from the other end edge section, each end section comprising a first wall portion and an associated second wall portion, both being elongated and of flexible material, with the associated wall portions overlapping for a part of the length of each, each wall portion having an inner edge section, with the inner edge sections of the second wall portions overlying their associated first wall portions and spaced from said end edge sections of said intermediate portion, and each wall portion having an outer end edge section; stretchable means connecting the edge section of one second wall portion with said intermediate portion at one end edge section of said intermediate portion; stretchable means connecting the end edge section of the other second wall portion with said intermediate portion at the other end edge section of said intermediate portion; bridging means connecting said end sections and extending over the back of a wearer of said brassière; and means securing said bridging means to the outer end edge sections of said wall portions.

2. In a brassière, an intermediate breast-supporting portion having opposite end edge sections and an upper edge section; a pair of end sections, one extending outwardly from one end edge section and the other extending outwardly from the other end edge section, each end section comprising a first wall portion and an associated second wall portion, both being elongated and of flexible material, with the associated wall portions overlapping for a part of the length of each, each wall portion having an inner edge section, with the inner edge sections of the second wall portions overlying their associated first wall portions and spaced from said end edge sections of said intermediate portion, and each wall portion having an outer end edge section; a lower edge section and an upper edge section; stretchable means connecting the edge section of one second wall portion with said intermediate portion at one end edge section of said intermediate portion and closely adjacent said upper edge section; stretchable means connecting the end edge section of the other second wall portion with said intermediate portion at the other end edge section

of said intermediate portion and closely adjacent said upper edge section; bridging means connecting said end sections and extending over the back of a wearer of said brassière; means securing said bridging means to the outer end edge sections of said wall portions; and means connecting each associated wall portion at its lower edge section, the upper edge section of each associated wall portion being free of direct attachment to the like upper edge section of its associated wall portion.

3. In a brassière, an intermediate breast-supporting portion having opposite end edge sections and an upper edge section; a pair of end sections, one extending outwardly from one end edge section and the other extending outwardly from the other end edge section, each end section comprising a first wall portion and an associated second wall portion, both being elongated and of flexible material, with the associated wall portions overlapping for a part of the length of each, each wall portion having an inner edge section, with the inner edge sections of the second wall portions overlying their associated first wall portions and spaced from said end edge sections of said intermediate portion, and each wall portion having an outer end edge section; a lower edge section and an upper edge section; stretchable means connecting the edge section of one second wall portion with said intermediate portion at one end edge section of said intermediate portion 30

and closely adjacent said upper edge section; stretchable means connecting the end edge section of the other second wall portion with said intermediate portion at the other end edge section of said intermediate portion and closely adjacent said upper edge section; bridging means connecting said end sections and extending over the back of a wearer of said brassière; means securing said bridging means to the outer edge sections of said wall portions, and means connecting each associated wall portion at its lower edge section, the upper edge section and outer end edge section of each associated wall portion being free of direct attachment to the like upper edge section and outer end edge section of its associated wall portion.
